UNITED STATES PATENT OFFICE.

JOHANNA DRAEMEL, OF FREMONT, NEBRASKA.

POSTAL CARD.

No. 894,124.

Specification of Letters Patent.

Patented July 21, 1908.

Application filed October 17, 1907. Serial No. 397,869.

To all whom it may concern:

Be it known that I, JOHANNA DRAEMEL, a citizen of the United States, residing at Fremont, in the county of Dodge and State of Nebraska, have invented new and useful Improvements in Postal Cards, of which the following is a specification.

The invention relates to an improvement in postal cards, and particularly to a combined letter sheet and postal card, the former providing an additional space for writing purposes and being adapted to be in part connected with the card to prevent unauthorized inspection.

15 The main object of the present invention is the provision of a postal card with which is associated and connected a writing sheet, the writing sheet being further provided with means whereby after use it may be additionally connected with the card and readily disconnected therefrom in the hands of the receiver.

20 The invention will be described in the following specification, reference being had particularly to the accompanying drawings, in which:—

Figure 1 is a face view showing the improvement, the letter sheet being extended. Fig. 2 is a rear view of the same.

25 Referring particularly to the drawings, my improved letter sheet 1 is designed for connection with an ordinary postal card 2, said letter sheet being preferably coextensive in size with the card and being secured to the upper edge of the card, either integrally or otherwise as is usual in return postal cards.

30 In the form illustrated the letter sheet is perforated or otherwise weakened along the line extending parallel to the normally free edge 3 of said sheet, as at 4, said weakened line being continued adjacent the side edges

35 40 45 of the letter sheet as at 6, the weakened extension 6, however, being in the preferred form of materially less length than the length of the side edge of the sheet. The relatively inner surface of the letter sheet between the free edges thereof and the weakened lines 3 and 6 is provided with usual adhesive material, as at 7.

In use the postal card and inner surface of 50 the letter sheet being written upon the latter is folded over on the postal card and the adhesive portion 7 thereof affixed to the card in the usual manner. As the adhesive material extends only ordinarily throughout the 55 length of the sides of the letter sheet it is obvious that there is provided above said adhesive material a length throughout which the letter sheet is free of connection with the postal card. This provides the necessary 60 opening required to permit the mail matter to be transported under the laws for the usual one cent stamp, while at the same time the partial securing of the sheet in place prevents that free access to the writing necessary 65 to read the same.

In the use of the invention described the receiver will, on desiring to read the inscribed matter separate the letter sheet from the card along the weakened lines of the 70 former, the operation of separation being obvious. Free access is thus permitted in a convenient manner to the proximate inscribed surfaces of the postal card and the letter sheet, and no danger of tearing the 75 letter sheet incurred.

Having thus described the invention what is claimed as new, is:—

A postal card and a letter sheet permanently connected to the card throughout one 80 edge of the latter, the free edge of the sheet being weakened along a line in spaced parallel relation to said edge, the weakened line extending along the side edges of the sheet being of materially less length than said 85 edges, the surface of the sheet between the edge and weakened line being provided with adhesive material which terminates coincidently with the termination of the weakened line. 90

In testimony whereof I affix my signature in presence of two witnesses:

JOHANNA DRAEMEL.
